BY HIS ATTORNEYS.

McClainson & Williamson

UNITED STATES PATENT OFFICE

HENRY E. BRANDT, OF NORTH ST. PAUL, MINNESOTA, ASSIGNOR TO NORTHWESTERN METALWARE COMPANY, OF MINNEAPOLIS, MINNESOTA, A CORPORATION OF DELAWARE

LIQUID FUEL BURNER STOVE

Application filed August 9, 1930. Serial No. 474,096.

This invention relates to liquid fuel burner stoves and it relates particularly to stoves of the type used for brooder stoves. In such brooder stoves, there is a casing which surrounds the burner head and this casing at its upper end is usually provided with an opening directly above the burner head closed by a cover plate. There is generally a spreader plate disposed in spaced relation above the burner head and this spreader plate prevents free access to the burner head when the cover plate is removed to permit of removal of carbon and dirt from the burner head. Also it is very difficult to obtain access to the burner head to light the liquid fuel therein, unless an opening is provided in the casing at one side of the same. Also it is often desired to adjust the height of the spreader plate relative to the burner head and to an apertured partition that is usually provided above the burner head and below the spreader plate.

It is the object of this invention to provide in a liquid fuel burner stove of the class described a construction whereby the spreader plate can be removed with the cover plate to permit of ready access to the burner head, a construction whereby the liquid fuel can be readily ignited without use of side doors in the casing of the stove and a construction wherein the spreader plate can be adjusted to and from the burner head, while the cover plate is applied to the casing.

To these ends the invention consists in the novel parts and novel combinations of parts, hereinafter defined in the claims and described in the following specification, made in connection with the accompanying drawings, wherein like reference characters refer to the same or similar parts throughout the various views, and, in which,

Fig. 1 is a vertical section taken through a liquid fuel burner stove of the type used for a brooder stove embodying the present invention, certain of the parts being shown in a lowered position in full lines and in a raised position in dotted lines; and

Fig. 2 is a view illustrating the lower portion of the rod shown in Fig. 1 with waste or similar starting material applied thereto.

Referring to the drawings, certain por-

tions of a liquid fuel brooder stove are illustrated, which include the base 3, cylindrical casing 4, burner head 5, partition plate 6, liquid fuel supply conduit 7, overflow conduit 8 and chimney 9. The casing 4 adjacent its lower end is provided with a series of air draft openings 10 and the burner head 5 may be formed integral with or secured to a horizontal divided plate 11 having a series of openings 13 therethrough to permit the circulation of air to the burner head. The burner head 5 has a well 12 at its central portion to which the liquid fuel is fed by means of the supply conduit 7 and one or more overflow grooves 14 concentric with the well 12 are provided in the burner head, the overflow conduit 8 being disposed in the outermost groove 14. The partition plate 6 is disposed in spaced relation above the burner head 5 in a horizontal plane and a central opening 15 is provided in the partition plate above the well 12 of the burner head. The top of the casing 4 may be provided adjacent one side of the casing with a flanged opening over which the smoke pipe 9 is placed. As is usual in such a stove, the top of the casing 4 is provided with a central down set portion having quite a large opening 16 therethrough, the down set portion having an inwardly projecting flange upon which a circular cover plate 17 may rest.

In accordance with the present invention, a rod 18 is centrally mounted in the cover plate 17 to project downwardly therefrom through the opening 15 in partition 6 and into the well 12 of the burner head 5. The cover plate 17 will preferably be provided with a screw threaded apertured hub and the upper end of the rod 18 will preferably be screw threaded to fit within the screw threaded aperture of the hub of the cover plate for adjustment of the rod upwardly and downwardly relative to the cover plate. A finger ring 19 is secured to the upper end of the rod 18 above the cover plate. A circular deflector plate 20 of smaller diameter than the central opening 16 in the top of the casing is secured to the rod 18 as by means of a set screw 21 below the cover plate 17 and in spaced relation above the partition 6. The

lower end of the rod 18 will preferably be pinched outwardly at its two sides to form small wings 22 for the retention of waste A or similar igniting material, as illustrated in

5 Fig. 2.

Due to the fact that the rod 18 is mounted in the cover plate 17 and the deflector plate 20 is carried by the rod 18, it will be seen that the cover plate and the deflector plate can 10 both be simultaneously raised with the rod 18 from the casing 4 to permit of free access through the opening 15 to the burner head 5 for cleaning carbon or other dirt therefrom. It will also be seen that the relative adjustment 15 between the deflecting plate 20 and the partition plate 6 and burner head 5 can be varied while the burner is in operation and while the cover plate 17 is fitted over the opening 16 by merely turning the rod 18 relative to the cover plate 17. To ignite the 20 burner when first starting the same, it is only necessary to raise the rod 18 out of the casing 4 thereby removing both the cover plate 17 and the deflector plate 20, whereupon 25 a small quantity of waste A or similar igniting material may be wound about the lower end of the rod 18, the wings 22 holding the waste in place. The rod and plates 17 and 20 can then be reinserted in place to dip the 30 waste A in the well 12 which will preferably have been supplied with a small quantity of liquid fuel, and the waste will then be impregnated with the fuel. The rod 18 can then again be removed from the casing and 35 the waste ignited whereupon by again reinserting the rod 18 and the two plates 17 and 20 in place, the fuel in the well 12 may be ignited by the flaming waste or similar igniting material.

40 It will be seen that a very simple construction is provided for effectively accomplishing the purposes intended. The present device has been amply and successfully demonstrated in actual practice.

45 It will, of course, be understood that various changes may be made in the form, details, arrangement and proportions of the various parts without departing from the scope of the present invention, and it will 50 further be understood that the present invention may be used in connection with broader stoves or in connection with any other type of liquid fuel burner stoves.

What is claimed is:—

55 1. A liquid fuel burner stove comprising a casing having an opening therethrough at its upper end, a burner head supported in said casing and having a well below said opening, means for supplying liquid fuel to said well, a cover plate fitting over said opening and a rod carried by said cover plate and projecting downwardly into said well whereby said rod and said cover plate may be simultaneously removed from said casing and lighting material may be applied

to the lower end of said rod dipped into said well to impregnate it with fuel, then lit and again dipped into said well to light said burner.

2. The structure defined in claim 1, said rod having means at its lower end for retaining waste and similar lighting material thereon. 70

3. A liquid fuel burner stove comprising a casing having an opening at its upper end, 75 a burner head supported in said casing and having a well below said opening, means for supplying liquid fuel to said well, a cover plate fitting over said opening, a rod mounted in said cover plate and projecting downwardly into said well, and a spreader plate of smaller diameter than said opening carried by said rod in spaced relation above said burner head, said rod, cover plate and spreader plate being simultaneously removable from said casing. 80

4. The structure defined in claim 3, said rod having a screw threaded portion and one of said plates having screw threaded engagement with said screw threaded portion 90 of said rod to permit of relative adjustment between said spreader plate and said burner head. 95

5. A liquid fuel burner stove comprising a casing having an opening therethrough at 95 its upper end, a burner head supported in said casing below said opening, means for supplying liquid fuel to said burner head, a cover plate fitting over said opening and a rod carried by said cover plate and projecting downwardly to a point adjacent said burner head, whereby said rod and cover plate may be simultaneously removed from said casing and lighting material may be applied to the lower end of said rod, dipped 100 into the liquid fuel supplied to said burner head, then lit and again reinserted in place to ignite the liquid fuel supplied to said burner head. 105

6. A liquid fuel burner stove comprising a casing having an opening therethrough at its upper end, a burner head supported in said casing below said opening, a partition in said casing above said head, said partition having a central opening above the central portion of said head, a cover plate fitting over said opening in said casing, a member carried by said cover plate and projecting downwardly through said opening in said partition, and a spreader plate carried by and supported solely from said member in spaced relation above said partition, said spreader plate being of smaller diameter than said opening in said casing whereby said cover plate, said member and said spreader plate may be simultaneously removed from said casing. 115

In testimony whereof I affix my signature.

HENRY E. BRANDT.
